UNITED STATES PATENT OFFICE.

JULIUS OTTO VON STETTEN, OF PHILADELPHIA, PENNSYLVANIA.

HOSIERY-DRYING FORM.

Application filed August 26, 1922. Serial No. 584,410.

To all whom it may concern:

Be it known that I, JULIUS OTTO VON STETTEN, a citizen of Czechoslovakia, residing at Philadelphia, county of Philadelphia, 5 and State of Pennsylvania, have invented a new and useful Improvement in Hosiery-Drying Forms, of which the following is a full, clear, and exact description, reference being had to the accompanying drawings, 10 which form a part of this specification.

This invention relates to an improvement in driers, and more particularly to devices for drying hosiery and similar articles, which are dried on shaping forms.

15 One of the objects of my invention is to provide a device of this character comprising a drying chamber which is arranged to hold a plurality of independent drying forms.

20 Another object of my invention is to so support the forms that each of the forms may be withdrawn from the chamber and returned thereto independent of the others.

Still another object of my invention is to 25 provide a separate closure for the chamber for each form, and which is supported directly on chamber walls or frame independent of the form supporting devices, so that the closures may be moved to their closed 30 positions, regardless of whether the forms are within or outside of the chamber.

A further object of my invention is to 35 provide automatic closure actuating mechanism under control of the form supports, which is arranged to be actuated at both ends of the movement of the form supporting devices, to open the closure at the beginning of the movement of the form and close it at the end of its movement, when the form 40 is moved into or out of the chamber.

The device illustrated comprises a drying chamber, having end and side walls, and a top formed of a plurality of pivoted slats, there being a slat for each form. The forms 45 are staggered with relation to each other and are mounted on supports which are journaled on rods or shafts extending along the side walls of the drying chamber, one-half being pivoted along one side while the other half is pivoted along the other side. The closures are pivoted on transverse axes and each is actuated by mechanism which is in turn actuated by the form support for the form in line therewith.

55 The precise nature of my invention will be best understood by reference to the draw-

ings which will now be described, it being premised, however, that various changes may be made in the details of construction and arrangement of the parts without departing from the spirit and scope of my invention as defined in the appended claims.

Fig. 1, is a plan view of one form of apparatus built in accordance with my invention.

Fig. 2, is an end view partially in section.

Fig. 3, is a detail sectional view on line 3-3 Fig. 1 with the form shown in vertical position.

Fig. 4, is a detail perspective view showing one of the form supports.

Fig. 5, is a detail end view partially in section, showing the actuating mechanism for one of the closure slats.

Fig. 6, is a detail sectional view of a portion of the drying chamber top.

Fig. 7, is an end view of Fig. 6.

The drying chamber is formed of a bottom 10, side walls 11 and end walls 12.

The top of the chamber is formed of a 80 plurality of slats 13, each of which is provided with a trunnion 14 at each end, which are pivoted in openings in the side walls 11, of the chamber. One of the longitudinal edges of each of the slats is provided with a flange 15 while the other edge is provided with a reversely extending flange 16, and 85 17 is a counter-weight on the flange 16. When the slats are closed the edges of adjacent slats overlie and underlie each other respectively as shown in Fig. 6, and in which figure the central slat is shown in its open position. 18 are stop pins for the slats, which are arranged to be engaged by the counter weights 17 when the slats are open 90 95 and 19 are similar pins which form supports for the slats when closed.

Mounted in the ends of the counter weights 17, are spring pressed plungers 20, see Fig. 7, which press upon the side walls 100 11 for the purpose of frictionally retarding the movement of the slats.

The side walls which are made of sheet metal are reinforced by angle irons 21 on the inside thereof and are also provided with vertical slots 22, for the forms as hereinafter described. As the forms are staggered with relation to each other as shown in Fig. 1, the slots in one side wall are also staggered with relation to the slots in the 105 other side wall.

The side walls are also reinforced on the

exterior by means of vertically disposed channel members 23, which also form guides for the slot actuating yokes hereinafter described.

5 Supported by brackets 24 are fixed shafts 25, which extend along the sides of the structure, and pivotally mounted on each of these shafts are a plurality of form supports 26. Each support is provided with a 10 turn table having a rotatable member 27 to which a hosiery drying form 28 is secured. This turn table is arranged to permit the form to be turned about an axis perpendicular to the axis of the support 26 to permit 15 the operator to adjust the stocking on the form. 29 is a detent for frictionally latching the form in its proper position for entrance to the drying chamber.

20 Slidably mounted in each channel member 23, is a yoke 30 having an upper rack 31 and a lower rack 32. 33 are pinions which are connected to the trunnion 14 of the slats, there being one pinion on each slat which coacts with its yoke. These yokes are arranged to slide between the flanges of their channel members which form side guides therefor, bottom guides being formed by the webs between the flanges of the channel members, while the top guides are formed 25 by covers 34, which extend between engage the free edges of the flanges of the channel members.

25 Each yoke is provided with upper actuating projections 35 and 36 at right angles to each other, and similar lower projections 37 and 38. These projections are engaged by dogs 39 and 40, the one being mounted on the hosiery form 28 while the other is mounted on a counter weight 60 on the support 26.

30 The dog 39 is provided with engaging hooks 41 and 42 for engaging the projections 35 and 36, respectively, while the dog 40 is provided with similar hooks 43 and 44 for engaging the projections 37 and 38, respectively.

35 The actuating mechanism between the form holders and the slats are all the same so that it will only be necessary to describe the manipulation of one of the forms, with particular reference to Fig. 4, in which all of actuating devices are clearly shown.

40 When the form is in the drying chamber the hooks 41 and 42 are engaged with the projections 35 and 36, and the rack 31 is in engagement with the pinion 33. In removing the form from the drying chamber, the counter weight or the support 26 is depressed to swing the support about shaft 25. 45 At the beginning of the upward movement of the form 28, the projection 42, will elevate the yoke 30 a sufficient distance to rotate pinion 33 clockwise to swing the slat 13 into its open position ahead of the form 50 28. As the form 28 approaches the upright

position shown at the right side of Fig. 1, hook 43 of the dog 40 will engage projection 37 and still further elevate yoke 30.

55 During this further elevation of yoke 30, rack 32 will rotate pinion 33 counter clockwise and swing the slat to its closed position, to prevent the escape of hot air during the removal from the form of one stocking, and the placing of another stocking on the form. 75

60 During the first movement of replacing the form into the drying chamber, hook 44 which is now in engagement with projection 38, will shift yoke 30, downward, to cause rack 32 to rotate pinion 33 clockwise to 80 again open slat 13 and permit the form to enter its slot 22, and the drying chamber. Just before the form reaches its position of rest on the reinforce 21, (which also forms a support forms when in the drying chamber) the hook 41 will engage projection 35 85 and shift the yoke 30 to its extreme lower position and during such movement the pinion 33 will be rotated counter-clockwise and close the slat 13 immediately after the form 90 is moved into the drying chamber.

65 Mounted in the lower portion of the drying chamber are headers 50, 50 shown at the left side of Figure 2, at one end and 51, 51 are similar headers at the other end shown 95 at the right side of Figure 2. The headers at one end are connected to the headers at the other end by pipes 52, 52, to form two steam radiators one above the other, 53 are steam inlet pipes extending into headers 50, having suitable control valves, and 54 are water outlet pipes leading from headers 51, 51, to a steam trap not shown. 100

70 55 is a fan box below the bottom of the drying chamber, but communicating therewith and which is provided with a fan 56, driven in any desired manner. The bottom of the fan casing is provided with inlet parts which are controlled by a grid 57 connected to an operating handle 58. 105

75 Air is sucked in through the parts and driven upwardly over the radiator whereby it is heated, to the top of the chamber over the stockings on the forms. This fan will also cause a continuous circulation of air 110 upwardly from the center and downwardly along the sides and ends of the chamber, and cause the air to pass in a continuous manner over the radiator. 115

80 The operator in charging moves from one end to the other, along one side, and successively charges the forms or removes the stockings and replaces them and then along the other side and then again along the first side. The device should have sufficient forms to allow enough time to dry the first stocking by the time the operator again reaches the first form which was charged. 120

85 The advantages of my invention result 125 from the provision of a drying device hav- 130

ing a plurality of drying forms which are arranged to be separately removed from the drying chamber, together with a closure for the drying chamber for each form, which is 5 arranged to be closed when the form is in drying position in the chamber or in charging position on the outside of the chamber.

Also from the provision of automatic means for first opening and then closing the 10 drying chamber when the form is moved into either drying position or charging position.

I claim:

1. A drier having a drying chamber, a 15 swinging form for an article to be dried, said form being supported to be swung into and out of the chamber, a closure for the chamber in line of movement of the form, and actuating connections between the form 20 and closure for moving the closure first to open and then to closed position, when said form is moved in either direction.

2. A drier having a drying chamber, a swinging form for an article to be dried, 25 said form being supported to be swung into and out of the chamber, a closure for the chamber in line of movement of the form, means for moving the closure to its open or closed position, and means actuated by the 30 movement of the form for moving said first mentioned means.

3. A drier having a drying chamber, a swinging form for an article to be dried, 35 said form being supported to be swung into and out of the chamber, a pivoted closure for the chamber in line of movement of the form, and actuating connections between the form and closure to first open the closure and then close the closure, when the form is 40 swung from one extreme position to the other.

4. A drier having a drying chamber, a plurality of separate forms for articles to be dried and arranged to be swung about 45 horizontal axes, a cover for the drying chamber comprising a pivoted slat for each form, said slats being arranged to co-operate with each other to form a complete cover for the chamber, and actuating connections between 50 each form and its respective slat to first open and then close the slat each time the form is swung.

5. A drier for hosiery having a drying chamber, with side walls, end walls and top, 55 a plurality of hosiery forms, pivoted on horizontal axes on opposite sides of the chamber, the forms on one side being staggered with relation to those on the other side, means for supporting said forms in sub-

stantially horizontal position when in drying position within the chamber and in substantially vertical positions when in charging position outside of the chamber, the top comprising a plurality of slats, 60 adapted to swing about horizontal axes perpendicular to the axes of the forms, there being a slat in the plane of movement of each form, and actuating connections between each form and its slat, to first swing the slat to its open position and then swing 65 it to its closed position, when the form is swung from either extreme position to the other extreme position, whereby each slot is closed when its form is in either of its extreme positions.

6. A drier for hosiery having a drying chamber provided with a bottom, top, sides and ends, means for heating the air in said chamber, means for causing the air to circulate in the chamber, a fixed longitudinal 80 shaft extending along each side of the chamber and on the exterior thereof, a plurality of supports on each shaft and arranged to swing thereon, a hosiery form turnably mounted on each support, the supports on 85 one side being in staggered relation to the supports on the other side, there being a slot in one of the side walls for each form, through which it extends when in drying position in the chamber, the top comprising 90 a plurality of slats arranged to swing about axes extending perpendicular to the shafts, there being a slat in the plane of each form, a pinion connected to each slat for swinging it into either open or closed position, a yoke 95 for each pinion slidably mounted on a side wall of the chamber, each yoke having two spaced racks adapted to independently actuate the pinion, the one rack being arranged to rotate the pinion in one direction 100 while the other is arranged to rotate the pinion in the reverse direction when the rack is moved in one direction and to rotate the pinion in the reverse directions respectively when the yoke is moved in the reverse direction, actuating projections on each yoke, and dogs carried by and arranged to engage the yokes for their respective slats, to first shift the yoke to open the slat at the beginning of its swinging movement and to close 105 its slat at the ending of its movement, so that each slat is closed when its form is in either of its extreme positions.

In testimony of which invention, I have hereunto set my hand, at Philadelphia, Pa., 115 on this 22nd day of August, 1922.

JULIUS OTTO VON STETTEN.
